INVENTOR

John M. Doherty,

UNITED STATES PATENT OFFICE.

JOHN M. DOHERTY, OF CRANBROOK, BRITISH COLUMBIA, CANADA.

FEED-BAG.

1,277,878.

Specification of Letters Patent.

Patented Sept. 3, 1918.

Application filed August 29, 1917. Serial No. 188,851.

To all whom it may concern:

Be it known that I, JOHN M. DOHERTY, a subject of the King of Great Britain, residing at Cranbrook, in the Province of British Columbia and Dominion of Canada, have invented certain new and useful Improvements in Feed-Bags, of which the following is a specification.

This invention relates to a feeding device 10 for animals and more particularly to certain improvements in a nose bag adapted to be attached to the head of the animal.

The primary object of the invention is to provide a nose bag having means associated therewith to automatically raise the bottom of the bag nearer the lips of the animal to which it is attached as the feed contained in the bag is consumed and the weight thereof diminishes.

Another object of the invention is to provide a nose bag of the character set forth which can be cheaply manufactured and sold and which, when in use, will at all times hold the feed contained therein in a position accessible to the mouth of the animal to which it is attached.

Figure 1 is a view showing the bag in an applied position.

Fig. 2 is a longitudinal sectional view of 30 the bag and

Fig. 3 is a perspective view of a detail.

In the drawings 1 indicates a standard type of nose bag which is preferably made from flexible material and has secured to 35 its upper edge the oppositely positioned rings 2—2 which are adapted to receive the loops 3—3 carried by the opposite ends of an attaching strip 4. Engaging the outer surface of the bag adjacent the upper edge 40 thereof are a pair of oppositely disposed plates 5, each of these plates is of the construction clearly shown in Fig. 3; the upper end of each plate being reduced and bent inwardly above the upper edge of the bag as indicated at 6, then carried downwardly to 45 extend along the inner side of the bag as indicated at 7, and again bent as at 8 to extend outwardly through the material of the bag and through an opening 9 formed 50 in the perpendicular part of the plate. These outwardly extending ends 8 of the plate are provided with openings 10 for a purpose to be hereinafter set forth.

A similarly connected pair of plates are 55 connected to the lower part of the bag with the perpendicular part 11 of each of these

plates extending upwardly toward the upper plates. These plates have their lower ends reduced and bent inwardly beneath the bottom of the bag as indicated at 12 and then carried upwardly through said bottom to extend a short distance along the inner sides of the bag as indicated at 13. The extreme ends of the plates are again bent as at 14 and extend outwardly through the 65 sides of the bag and through the openings formed in the perpendicular parts of the plates.

The extended ends 11 of the lower plates are positioned in vertical alinement with the 70 extended ends of the upper plates and are equipped with an opening similar with those formed in the ends 8. These alined extensions of the upper and lower plates are adapted to be connected by coiled springs 75 15—15 each of which has one end thereof fastened in the end of one of the extensions 8, and the opposite end thereof fastened in the opening in one of the extensions 14.

As shown these springs are under tension 80 and normally tend to contract and thus raise the bottom of the bag nearer to the top edge thereof. When the bag is secured in position as shown in Fig. 2 the weight of the feed contained therein is sufficient to 85 normally hold the bottom in extended position, but as the feed is consumed and the weight thereof diminishes, these springs will raise the bottom of the bag nearer to the mouth of the animal thus allowing all the 90 feed in the bag to be readily consumed.

In the foregoing I have described only a preferred embodiment of the invention. It is to be understood that I reserve the right to make such changes in the construction 95 and arrangement of the various parts thereon as may be desired providing of course that the changes contemplated come within the scope of the appended claims.

I claim:—

1. A nose bag, including a flexible receptacle, plates secured to the upper and lower edges of said receptacle, each of said plates having an end thereof bent to pass through a portion of the receptacle and to provide a 105 projection extending outwardly therefrom, the projection of the lower plates being vertically alined with the projection of the upper plates, and springs connecting said alined projection.

2. A nose bag, including a flexible receptacle; plates secured to opposite points of

100

105

110

said receptacle adjacent the upper edge thereon, each of said plates provided with an opening and having the upper end therein reduced and bent inwardly above the upper edge of the receptacle, said reduced end being then carried downwardly along the inner surface of the receptacle, and again bent to extend outwardly through the one side of the receptacle and through the opening of the plate, duplicate plates secured to the lower part of the receptacle and having other outwardly projecting ends alined vertical with the outwardly projecting ends of the upper plates and springs connecting the projecting ends of said alined plates.

3. A nose bag including a flexible recep-

tacle, plates secured to the upper and lower ends thereof, each of said plates being bent to provide portions engaging opposite sides of the receptacle and having one end extended to provide a projection extending outwardly from the receptacle, and springs connecting the projections of the upper and lower plates to raise the bottom of the bag as the feed therein diminishes.
